UNITED STATES PATENT OFFICE.

WILLIAM C. FOWLER AND WILLIAM G. SCHAEFER, OF ST. LOUIS, MISSOURI.

BAKER'S OVEN.

SPECIFICATION forming part of Letters Patent No. 380,561, dated April 3, 1888.

Application filed February 21, 1887. Serial No. 228,399. (No model.)

To all whom it may concern:

Be it known that we, WILLIAM C. FOWLER and WILLIAM G. SCHAEFER, both citizens of the United States, and residents of the city of 5 St. Louis, in the State of Missouri, have invented certain new and useful Improvements in Bakers' Ovens, of which the following is a full, clear, and exact description, reference being had to the accompanying drawings, forming part of this specification, and in which—

Figure I is a front view of our improved oven, part in section. Fig. II is a transverse vertical section at II II, Fig. III. Fig. III is a longitudinal vertical section at III III, Fig. 15 I. Fig. IV is a longitudinal vertical section at the jagged line IV IV, Fig. II. Fig. V is a horizontal section on the line V V, Fig. II. Fig. VI is a horizontal section on the jagged line VI VI, Fig. II.

20 1 is the front wall; 2, the side walls; 3, the back wall, and 4 the top.

5 5 are the ash-pits under two similar furnaces, 6.

7 is the wall separating the two furnaces and 25 the combustion-chambers 8, into which the products of combustion pass from the furnaces.

9 is an air-heating flue made in the wall 7 and extending from the front backward, as 30 shown in Fig. VI. The flue has side openings, 10, leading into the combustion-chambers to supply hot air to assist in the combustion of the gases.

11 11 are the bridge-walls of the furnaces 6.

Each combustion-chamber is separated at 35 its lower part by a longitudinal wall, 12, and is spanned by an arch, 13, a space or opening, 14, being left between the top of the wall and the arch for the passage of the gases. From the air-heating flue there are flues 15 extending 40 upwardly, laterally, and downwardly through the brick-work of the arches and open at the top of the arches, where they discharge the hot air down into the space or opening 14 to cause the combustion of any inflammable gases 45 remaining. The products of combustion escape from the second compartment, 16, of each combustion-chamber through a number of openings, 17, in the side wall into a chamber, 18, in said wall, which extends upward and forward to an opening, 19, into a flue-chamber, 20, above the oven proper or baking-chamber

21. The two openings 19 are at the front outer corners of the flue-chamber. (See Fig. V.)

22 and 23 are a number of deflectors extending transversely from the floor of the chamber 55 20 to its top. The deflectors 22 extend from the sides of the chamber 20 to near its middle, and the deflectors 23 extend nearly to each side wall. The effect of these deflectors is to cause the heated products of combustion from each 6c furnace to mingle together at the middle of the chamber 20 at the front part, and then to form into two currents, moving outward to the sides, and then converge, and so on, as indicated by the arrows in Fig. V, until the said products 65 reach the discharge-opening 24, leading to the chimney or smoke-stack 25.

26 is the door of the baking-chamber or oven proper.

27 are peep-holes to the oven.

We claim as our invention—

1. A baker's oven formed with a furnace, 6, bridge-wall 11, and combustion-chamber at the rear of the bridge-wall, having a longitudinal wall, 12, dividing the chamber into two parts, 75 8 and 16, and leaving a space or opening, 14, at the top, substantially as described.

2. A baker's oven formed with a furnace, 6, bridge-wall 11, a combustion-chamber at the rear of the bridge-wall, side flues, 17, a baking-chamber, 21, over the furnace and chamber, flue-chamber 20 over the baking-chamber, a chimney at the rear part of the flue-chamber, and wall-chamber 18, communicating with the side flues and extending upward and forward to the flue-chamber, substantially as described.

3. A baker's oven formed with two furnaces, 6, bridge-walls 11, combustion-chambers at the rear of the bridge-walls, side flues, 17, a baking-chamber, 21, over the furnaces and chambers, a flue-chamber, 20, over the baking-chamber, having openings 19 at the front outer corners, deflectors 22, extending from the sides to near the middle, deflectors 23, extending to 95 near each wall, and a chimney at the rear end, and the wall-chambers 18, extending from the side flues to the corner openings, substantially as described.

4. The combination, in a baker's oven, of a 100 furnace and a combustion-chamber, a side wall of the furnace and chamber being formed with

air-heating pipe and side openings into the combustion-chamber, and the top of the combustion-chamber being formed with flues connecting with the air-heating pipe discharging into the chamber, substantially as described.

5. The combination, in a baker's oven, of two furnaces, 6, side by side, bridge-walls 11, combustion-chambers side by side in rear of the bridge-walls, a longitudinal wall, 7, separating the furnaces and combustion-chambers, and an air-flue, 9, extending through the wall, having side openings, 10, into the combustion-chambers, substantially as described.

6. The combination, in a baker's oven, of 15 two furnaces separated by a wall and two combustion-chambers, one in communication with each furnace, and separated by the same wall, an air-heating flue passing into the wall, arches extending over the combustion-chambers, longitudinal walls extending from the bottoms of the combustion-chambers to near the arches, and air-passages extending from the air-heating pipe to the sides and tops of the combustion-chambers, for the purpose set forth.

7. The combination, in a baker's oven, of 25 two furnaces, two combustion-chambers, one in connection with each furnace, longitudinal walls 12, extending from the bottom to near the top of said chambers, a wall separating the furnaces and combustion-chambers, an air- 3c heating flue, 9, in the wall, branches 10 and 15 of the flue discharging into the sides and tops of the combustion-chambers, flues 17, leading from the outer sides of the combustion-chambers into the chambers 18, flues leading 35 from the chambers 18 to the front parts of the chamber 20, discharge-flue from the rear of chamber 20, and walls 22 and 23 in said chamber, arranged substantially as and for the purpose set forth.

WILLIAM C. FOWLER.
WILLIAM G. SCHAEFER.
